FURNACE FOR SINTERING METALLIC FILAMENTS FOR ELECTRIC INCANDESCENT LAMPS.

1,028,832.

Specification of Letters Patent.

Patented June 4, 1912.

Original application filed January 21, 1911, Serial No. 603,852. Divided and this application filed May 5, 1911. Serial No. 625,334.

To all whom it may concern.

Be it known that we, CARL TRENZEN, a subject of the German Emperor, and resident of Koeln-Braunsfeld, in the Province 5 of Rhineland, Kingdom of Prussia, German Empire, and ERNST HAAGN, a subject of the Emperor of Austria-Hungary, and resident of Hanau, in the Province of Hesse-Nassau, Kingdom of Prussia, German Empire, have 10 invented new and useful Improvements in Furnaces for Sintering Metallic Filaments for Electric Incandescent Lamps, of which the following is a full, clear, and exact specification.

15 This invention relates to an improved furnace for sintering filaments of tungsten or similar metal, which have previously undergone the usual decarbonizing treatment.

This sintering process has for its object 20 to eliminate the last traces of carbon and to impart to the filaments a more dense structure as well as a greater durability. Heretofore this sintering process has been performed by causing an electric current to 25 pass through each filament in the presence of a reducing gas. It has been proposed to externally heat such filaments in an atmosphere of such reducing gas without however, passing an electric current therethrough, in 30 order to allow a certain number of filaments to be treated simultaneously. Second class conductors have been proposed as a material suitable for the sintering furnaces. Furnaces of this kind, however, have been 35 found objectionable for the reason that for heating such furnaces by means of an electric current very high voltages are necessary and that in consequence, when the filament comes into contact with the inner side of the 40 furnace, which could not always be avoided, the electric current will not pass through the furnace, as it should do, but through the filaments themselves, which was the very thing to be avoided. Moreover, furnaces 45 consisting of second class conductors are liable to be destroyed by reason of the diminished resistance occurring at high temperatures and by reason of the consequent increase of the passing current. It has also 50 been proposed to employ a furnace of iridium, but it was practically remarked that in such case care must be taken to pre-

vent the filaments from coming into contact with the incandescent sides of the furnace and thereby being baked thereto under the 55 fritting action. To this end it had been proposed to coat the furnaces with second class conductors or to introduce the filaments into the furnaces by means of special carriers composed of the said material. A coating 60 of this kind, however, does not last and will crack off by reason of the difference in the coefficient of expansion of the iridium and coating material, and the employment of special carriers of such materials presents 65 certain difficulties, apart from the fact that it is not always possible to avoid contact with the inner sides of the furnaces with any degree of certainty.

We have found that the objections connected with the use of iridium furnaces are only experienced in such cases where the iridium employed is, as has always been the case heretofore, associated with other metals of the platinum group, more especially 75 ruthenium, rhodium and platinum. When impurities of this kind are present even to a very moderate extent the metal of which the furnace consists can form an alloy with tungsten, and this will after a very short 80 period of time result in destruction of the furnace. On the other hand, when employing a really pure iridium for the construction of the furnace there will be no danger of the filaments adhering to the inner sides 85 of the furnace by fritting.

The object of our invention is to obviate the difficulties and objections connected with the furnaces heretofore employed in sintering metallic filaments of the kind above referred to, and to this end our invention consists in the sintering furnace hereinafter to be more fully described and shown in the drawing, which shows an example of a furnace adapted for carrying out the improved 95 process.

The essential feature of our invention is a tube of pure iridium in which the filaments which have undergone the usual preliminary decarbonizing treatment are sintered by external heat without an electric current being allowed to flow through the filaments. This external heat is produced by heating the iridium tube by any appropriate means, and

preferably by an electric current. In this way it is possible to practically realize the object already aimed at heretofore, but not so far successfully attained, of simultaneously treating a multiple number of filaments without an electric current passing therethrough.

In the drawing the furnace is shown in perspective with parts broken away.

10 As here shown a suitable standard 1 carries a frame 2 which supports the furnace within an opening provided for the purpose in a transverse part 3 of the frame 2, the raised edge 4 of the said opening preventing lateral displacement of the furnace.

15 The furnace itself embodies the following parts: 5 is a tube of pure iridium open at its lower end and closed at the top. By means of contact members 6 and 7 of a suitable conducting material, preferably platinum, the said tube is connected with two plates 8 and 9 preferably of nickel. These contact members 6 and 7 are preferably so constructed as to be capable of 20 a certain spring action, to thereby permit free expansion of the iridium tube 5 under the action of heat without thereby interfering with the supply of elastic current. The plates 8 and 9 are supported on threaded 25 bolts 10 secured to the transverse part 3 of the frame 2. A tube 11 of refractory material, preferably magnesia, surrounds the iridium tube 5 without, however, contacting therewith at any point. The magnesia tube 30 is surrounded by a cooling jacket 12 preferably made of nickel and adapted to have a cooling medium, such as water, supplied thereto through a pipe 14 which is provided with a cock or valve 13. 15 is a pipe for the 35 discharge of the water from the cooling jacket 12. The lower portion of the iridium tube 5 is also surrounded by a cooling jacket 16 to which cooling water is admitted through a pipe 17. The discharge of the 40 water may be effected by means of a suitable pipe provided on the rear side, but not visible in the drawing. Another cooling jacket 18 having a water supply pipe 19 and a discharge pipe 20 also surrounds the upper 45 portion of the iridium tube 5.

50 The iridium tube 5 is provided at its upper end with a pipe 21, preferably made of platinum, adapted to have a suitable reducing gas, such as hydrogen or ammonia, supplied therethrough. Another pipe 22, preferably also formed of platinum, serves for conveying the said reducing gas into the space between the iridium tube 5, on the one hand, and the magnesia tube 11 or the 55 cooling jacket 12, on the other hand, the said gas then escaping at the lower end of the cooling jacket. It is of importance to thus admit gas exteriorly in order to thereby prevent the rather thin and delicate iridium 60 tube from being destroyed under the action 65

of inner pressure and in order to secure the pure condition of the gas which is passed through the iridium tube.

70 The parts of the furnace are held together by two cross pieces 23 and 24 secured to the threaded bolts 10 already referred to by means of threaded nuts 25. The nickel plates 8 and 9 are provided with binding screws 26 for connecting an electric circuit thereto. Similar binding screws are also 75 provided at those corners of the nickel plates which are not visible in the drawing. The nickel plates 8 and 9 as well as the contact members 6 and 7 of the iridium tube 5 must be insulated from other metallic parts by 80 suitable layers 27 of insulating material, such as asbestos slate, for instance.

85 On a cross piece 28 of the standard 1 are mounted two guide rods 29, 30 between which a rack bar 31 is arranged to slide upward and downward the said guide rods engaging in suitable grooves provided on the opposite sides of the guide rods. A pinion 32 rigid on the shaft 33 suitably journaled in bearings 34 of the standard 1 engages with 90 the teeth of the rack bar, and by rotating the said shaft and its pinion 32 by means of its hand wheel 35 the rack bar may be caused to move upward or downward. The 95 said rack bar carries a holder 36 which is 95 formed at its upper end for suspending therefrom the metal filaments 37 to be treated. This top portion of the carrier 36 at least should also consist of pure iridium. For the sake of clearness of the drawing only a few filaments are shown as suspended from the holder, but in the practical use of the invention a greater number of filaments will be suspended therefrom.

100 The practical operation is as follows: An 105 electric current suitable for imparting to the iridium tube 5 the proper temperature, say 1400-1600° C. is supplied to the iridium tube 5 by way of the binding screws 26, nickel plates 8, 9 and contact members 6, 7 and caused to pass through the iridium tube 5, such currents being admitted at a number of points simultaneously through the binding screws 26, since currents up to 1500 amperes are required. The filaments, after having 110 been preliminarily heated at a temperature of about 1250° C. in the well known manner, are assembled on the holder 36, and by rotating the hand wheel 35 the said holder is raised and thereby moved into the iridium tube 5 from below so that the filaments suspended therefrom will enter the highly heated portion of the said tube. During the 115 operation a current of a reducing gas, such as hydrogen or ammonia, is introduced 120 through the pipes 21 and 22, the passage of gas being so regulated that the gas will become substantially consumed and no generation of injurious gases can take place at 125 the lower end to any appreciable extent. 130

The filaments having been allowed to remain in the iridium tube for about one minute the holder is then lowered by rotation of the hand wheel 35 in the opposite direction to thereby cause the filaments to be removed from the tube again. While doing so the filaments will pass the cooled lower portion of the iridium tube and will thereby themselves undergo a sufficient cooling. The operation is then repeated with a fresh quantity of filaments. Provision may also be made for introducing the filaments into the iridium tube from above instead of from below as hereinbefore described, but in that case the top end of the iridium tube will have to be provided with an opening for introducing the filaments, and such opening will have to be provided with means for closing the same. In this case provision will also have to be made for suitably admitting the gas laterally.

What we claim is:

1. In a sintering furnace the combination of a tube of pure iridium, means for passing electric current through said tube for heating the latter, a surrounding body of refractory material out of contact with said tube, cooling devices surrounding said tube and refractory body, means for admitting gas to the interior of said tube and between the tube and the surrounding body and cooling devices, and means for introducing filaments into said tube.
2. In a sintering furnace the combination of a tube of pure iridium arranged to freely expand and contract under the influence of temperature variations, means for passing

electric current through said tube for heating the latter, a surrounding body of refractory material out of contact with said tube, cooling devices surrounding said tube and refractory body, means for admitting reducing gas to the interior of said tube and between the tube and the surrounding body and cooling devices, and means for introducing filaments into said tube.

3. In a sintering furnace the combination of a tube of pure iridium arranged to freely expand and contract under the influence of temperature variations, means for passing electric current through said tube for heating the latter, a surrounding body of refractory material out of contact with said tube, cooling devices surrounding said tube and refractory body, means for admitting reducing gas to the interior of said tube and between the tube and the surrounding body and cooling devices, a suspension device of pure iridium for carrying the filaments, and means for introducing said suspension device and filaments into said tube.

In testimony, that we claim the foregoing as our invention, we have signed our names in presence of two subscribing witnesses.
